E. W. BRANCH, OF EAST HENRIETTA, NEW YORK.

Letters Patent No. 66,207, dated July 2, 1867.

IMPROVEMENT IN CIDER-MILLS.

The Schedule referred to in these Letters Patent and making part of the same.

TO ALL WHOM IT MAY CONCERN:

Be it known that I, E. W. BRANCH, of East Henrietta, in the county of Monroe, and State of New York, have invented certain new and useful improvements in Apple-Grinding Machines; and I hereby declare that the following is a full and exact description thereof, reference being had to the accompanying drawings, making part of this specification.

Figure 1 is a section of the machine, but looking on the back side of the grinding apparatus.

Figure 2, a section through the hopper, looking on the front side of the grinding apparatus.

Figure 3, a vertical section, at right angles to figs. 1 and 2.

Figure 4, a section of the hopper, looking the opposite way from fig. 2.

Figure 5, a diagram in perspective, showing the engagement of the jointed pawl with the stop, by which motion is given to the grinding-wheel.

Like letters of reference indicate corresponding parts in all the figures.

My improved machine is intended for grating rather than crushing the apples. The invention consists in an improved arrangement of parts whereby the grinding and balance-wheels are disengaged from the driving power when the latter stops, so as not to produce shock or strain; also in securing the grating-wheel in a rim of the balance-wheel so that it is made removable; also in the employment of an adjustable bed for holding the apples to the grating-wheel; and finally, in the employment of a space between the spring-board in the hopper and the bed for the passage of stones, &c.

As represented in the drawings, A is a frame, in which is mounted a band or crank-wheel, B. This wheel has an internal gear, *a*, with which gears a pinion, *b*, of a shaft, *c*. At the opposite end of *c* is situated a balance-wheel, C, and grinding-wheel, E, whose hub, *d*, fits loosely thereon. The end of the shaft, inside the hub, is provided with a pawl, D, made up of two parts, a fixed arm, *f*, and a jointed dog, *g*, as clearly shown in figs. 1 and 5. In turning rapidly forward the centrifugal action will extend or throw the pawl out, as in black lines, and in this condition its end strikes a stop or shoulder, *h*, of the wheel, and thus connects the latter with the shaft and gives it motion. But when the shaft is stopped, the stop *h*, coming around on the opposite or back side of the pawl, will strike the dog *g* and depress or throw it down, as shown in red lines, and the grinder will then revolve free till it slackens and stops. The advantage of this arrangement is that when the shaft is stopped from any cause the continued turning of the wheel will not produce a sudden shock or strain upon the driving power from the centrifugal action, as would be the case if the grinder were rigid with the shaft. The wheel can move on without impediment. In addition to this the automatic disengagement of the pawl will allow the wheel to be turned backward, as well as forward. It is frequently the case that the grinding apparatus becomes clogged with stones or other impediments which require the wheel to be turned back to disengage them. If an ordinary pawl and ratchet were employed, this could not be accomplished without raising the pawl. In my case, when the shaft is stopped the wheel is free to turn either forward or backward. The grinding-wheel, E, instead of being of cast iron, as usual, is made in the form of a wooden disk, armed with teeth *i* driven therein; and this disk is simply inserted in a rim, *k*, which is cast with the balance-wheel. It is held in place by screws or bolts, and in this manner it is made removable. Thus, if the grinding face is at any time injured by stones passing through, or from other sources, the whole machine is not ruined, but the grinding disk may be removed from its place and a new one substituted without difficulty. If a stone passes through, the wood will also indent and yield, and therefore there is less liability of breakage than when a solid iron face is employed. The teeth *i* are much more effective in grating and reducing the apples than any that can be cast upon an iron face, which acts only to crush instead of grate the apples. In front of the grinding-wheel is situated a hopper, G, and beneath it is situated a discharge-spout, H. The hopper rests against one side of the face, and the spout opens centrally from under it, being so relatively arranged with the wheel that while the whole grinding surface is economized the space below will insure the throwing off of the pomace by the centrifugal action, as indicated by the arrows, fig. 2. In the bottom of the hopper is situated a curved bed, I, formed of a strip of metal of suitable size, as clearly indicated. This is adjusted toward or from the grinding-wheel by slots and screws *l*. This bed enables the throat for the passage of the apples to be enlarged and contracted, as may be desired; and being made thin at the operating edge it facilitates the escape

of the pomace at that point, where, if a thick throat were employed, it would become choked and clogged. It also insures the apples being grated up finely, instead of being crushed as in the usual way. The hopper is provided with a board, K, pressed forward by a spring, m, which has a tendency to throw the apples up against the face of the grinder. This board does not extend clear to the bottom of the hopper, but a space, n, is left between its lower end and the bed I, as clearly shown in figs. 3 and 4. This space is of much importance, for it forms a receptacle for such stones as may pass down into the hopper, the stones pressing back into the space instead of passing through the throat. The grinding-teeth and the bed are thus shielded from harm, while the advantage of a spring-board is obtained to press the apples forward.

What I claim as my invention, and desire to secure by Letters Patent, is—

The combination and arrangement of the spring-board K and adjustable bed I with the grinding apparatus, consisting of the disk E, fitting in the rim h of the wheel C, which is driven by jointed pawl D, the whole constructed as described and operating in the manner and for the purpose herein set forth.

In witness whereof I have hereunto signed my name in the presence of two subscribing witnesses.

E. W. BRANCH.
